Primary Examiner—Martie Thompson**Attorney, Agent, or Firm**—Knobbe, Martens, Olson & Bear L.L.P.[57] **CLAIM**

The ornamental design for a cervical pillow, as shown and described.

DESCRIPTION

FIG. 1 is a top perspective of the design of the present invention;

FIG. 2 is a rear elevational view thereof;

FIG. 3 is a top plan view thereof;

FIG. 4 is a right side elevational view thereof, and is a mirror image of the left side elevational view;

FIG. 5 is a front elevational view thereof; and,

FIG. 6 is a cross-sectional view of the design of the present invention taken along lines 6—6 in FIG. 3.
